UNITED STATES PATENT OFFICE.

GEORGE M. HOPKINS, OF BROOKLYN, ASSIGNOR TO THE ECONOMIC MOTOR COMPANY, OF NEW YORK, N. Y.

DESIGN FOR AN ENGINE-FRAME.

SPECIFICATION forming part of Design No. 14,024, dated July 3, 1883.

Application filed May 24, 1883. Term of patent 14 years.

To all whom it may concern:

Be it known that I, GEORGE M. HOPKINS, of Brooklyn, in the county of Kings and State of New York, have invented and produced a new and original Design for a Gas-Engine Frame, of which the following is a full, clear, and exact description, reference being had to the accompanying drawing.

The leading feature of my design consists in a vertical cylinder with radial ribs having curved upper ends and parallel sides, and in a frame projecting from one side of the cylinder, with a curved top and a straight side parallel with the cylinder; also, in a base with curved ends and sides, and with a portion of the upper and lower edges of the sides cut away.

A is the cylinder of the engine, and B B B B are ribs with parallel edges and curved tops, projecting radially from the cylinder. C is a frame projecting from one side of the cylinder A, with a curved top, *a*, joining the top of the cylinder A, and the bearing *b*, and a straight side, *c*, extending from the bearing *b* to the base. The frame C has four panels, *d*, formed by four ribs, *e*, radiating from the bearing *f*. The base D is curved outward in opposite directions at the ends, and is cut away at *g h* at

its upper and lower edge, at the sides, as represented in the drawing.

30

I claim—

1. The design for a gas-engine frame herein shown and described, the same consisting of the vertical cylinder A and the frame C, with curved top *a*, joining the bearing *b* and the top of the cylinder A.

2. The design for a gas-engine frame herein shown and described, the same consisting of the vertical cylinder A, with radial ribs B, curved at the top, and the frame C, with the curved top *a* and straight side *c*.

3. The design for a gas-engine frame herein shown and described, the same consisting of the cylinder A, with radial ribs B, and the frame C, with the curved top *a*, straight side, 45 *c*, and panels *d*.

4. The design for a gas-engine frame herein shown and described, the same consisting of the base D, with curved ends and cut-away upper and lower edges, the cylinder A, with 50 radial ribs B, and frame C, with curved top *a*.

GEO. M. HOPKINS.
